TWO-NEEDLE BUTTON SEWING
MACHINE

Joseph Vollman and Hermann Gunther, Elizabeth, N. J., assignors to The Singer Manufacturing Company, Elizabeth, N. J., a corporation of New Jersey

Application February 13, 1937, Serial No. 125,522

7 Claims. (Cl. 112—112)

The present invention has for an object to provide an improved two-needle button sewing machine for sewing on four-hole buttons with two simultaneously formed but entirely disconnected groups of button-fastening stitches; there being no cross-threads between the two groups of stitches at either side of the work.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

Fig. 1 is a side elevation, partly in section, of a two-needle button-sewing machine embodying the invention. Fig. 2 is a bottom plan view of the machine. Fig. 3 is a bottom plan view of the throat-plate of the machine, showing the duplex thread-cutting and thread-end-nipping mechanism carried thereby. Fig. 4 is a section on the line 4—4, Fig. 1. Fig. 5 is a perspective view of the looper-carrying bracket shown in Fig. 2 at the free end of the work-supporting arm of the machine. Fig. 6 is an enlarged view showing the cooperation of the needles, loopers and loop-positioning and spreading means at the time in a stitch-forming cycle when the loopers are seizing new needle loops and are about to pass such loops through the previously seized loops on the respective loopers. Fig. 7 is a view of the parts as seen from the left side of Fig. 6. Fig. 8 is a similar view of the parts as seen from above with the button and work-supporting parts omitted, and Fig. 9 is a view similar to Fig. 7 but at a time in the cycle when the new needle-loops have been drawn out and are about to receive their customary half-twists by the wings of the respective loopers.

The sewing machine has a frame of usual construction comprising a bed 1, from which rises the standard 2 of the overhanging bracket-arm 3 terminating in the head 4.

Journalized in the bracket-arm 3 is the rotary main-shaft 5 which, through the crank 6 and link 7, drives the reciprocating needle-bar 8 carrying the spaced eye-pointed needles 9. The spacing of the needles 9 is equal to that of the holes of a four-hole button, so that by vibrating the button transversely of the plane of the needles, two separate groups of button-fastening stitches may be sewn through the four holes in the button.

The main-shaft 5 is geared one-to-one to the vertical shaft 10 which, in turn, is geared one-to-

one to the looper-shaft 11 journaled in the bed 1. The looper-shaft 11 carries the axial shank 12' of one of the loopers 12, which loopers are of the rotary chain-stitch type. The axial shank 12' of the other looper 12 is carried by a short looper-shaft 13 journaled in the bed-bracket 14 coaxially with the first mentioned looper-shaft 11. The bed-bracket 14 is detachably fastened to the bed 1 by means of the screws 15 and has also journaled in it the transmission shaft 16 which receives motion from the looper-shaft 11 through the spur gears 17, 17 and drives the short looper-shaft 13 through the spur-gears 18, 18; the two coaxial looper-shafts 11 and 13 being connected to run at the same speeds and in timed relation to one another.

The two loopers 12 are of right and left hand but otherwise identical formation. Each has a loop-seizing beak 19 and a loop-spreading wing 20. The shank or spindle 12' of each looper is mounted in a socket in the respective looper-shaft. Each looper is formed adjacent the base of its supporting shank or spindle 12' with an arcuate loop-spreading shoulder 22 the function of which is to hold the inclined limb of the previously seized needle-loop high enough so that the looper-beak will, after seizing a new needle-loop, pass it through the previously seized loop, as shown in Figs. 6, 7 and 8.

Cooperating with the needles 9 and loopers 12 is a loop-positioner 23 in the form of a Y-shaped member the stem 24 of which is curved in a vertical plane, Fig. 6, about the loopers 12 and is supported by the rock-shaft 25 which is journaled in the bed 1 below the looper-shaft 11. The looper-shaft 11 carries a cam 11^a, Fig. 4, which actuates the follower-roll 11^b at the end of the follower-arm 11^c fixed to the rock-shaft 25. The cam 11^a moves the loop-positioner 23 from the retracted position, shown in dotted lines in Fig. 6, to its effective position shown in full lines in Figs. 6, 7 and 8. The cam 11^a is timed to advance the loop-positioner as soon as the needle-loops 27 have been well drawn down or expanded by the loopers 12, as shown in Fig. 9. The divergent horns of the Y-shaped loop-positioner 23 gather together the limbs of the previously seized and expanded needle-loops 27 and position them in a bunch 28 between the paths of the needles 9 which descend at opposite sides of the stem 24 of the loop-positioner and the bunched limbs 28 of the needle-loops positioned thereabove. The loop-positioner 23 remains in its advanced position until the loopers have seized new needle-loops 29 and carried them safely through the re-

spective previously formed loops 27. By referring to Figs. 6 and 7, it will be observed that the arcuate loop-spreading shoulders 22 of the loopers 12 hold the inclined portions 30 of the needle-loops high enough for the beaks 19 of the loopers to pass therebelow.

Secured upon opposite sides of the stem 24 of the loop-positioner 23 are the needle-guards 31 which are spaced sufficiently from the stem 24 to admit the needles 9. The needle-guards 31 prevent the needles from being accidentally struck or caught by their respective looper-beaks. The stem 24 of the loop-positioner also has a needle-positioning function in holding the needles correctly spaced apart for the loop-seizing action of the loopers.

The button 32 is held upon the fabric 32' by the button-gripping jaws 33 of the usual button-clamp 34 which includes the work-supporting plate 34' and is vibrated transversely of the plane of the needles 9 by the usual clamp-shifting mechanism such as disclosed in U. S. Patent No. 1,093,241, of Apr. 14, 1914. Such mechanism includes a feed-cam 35 which is given a slow rotary motion by the worm-and-gear connection 36 with the main-shaft 5. The feed-cam of the present machine is designed to vibrate the work-clamp laterally of the bed 1; no motion being imparted to the work-clamp longitudinally of the bed 1.

On the rearward end of the main-shaft 5 are mounted the usual tight and loose pulleys 37, 38, respectively, of a common form of start-and-stop-motion device including the starting and stopping lever 39 which is pivoted to the machine frame at 40 and carries the belt-shipper 41 and stopping tooth 42; the latter cooperating with the usual notched stop-cam 43. The details of this stop-motion device are more fully disclosed in U. S. Patent No. 1,093,241 above referred to.

The machine is fitted with thread-cutting and thread-end-nipping mechanism, such as disclosed in U. S. Patents No. 1,251,451, of Dec. 25, 1917 and No. 1,549,248, of Aug. 11, 1925. In the present instance the thread-cutters 44 are right and left counterparts and are carried by the thread-cutter lever 45 which is fulcrumed at 46 on the under side of the throat-plate 47 and actuated in the usual manner as disclosed in said patents. The thread-end nippers 48, also right and left counterparts, are carried by the usual thread-end-nipper lever 49 which is fulcrumed at 50 on the throat-plate 47 and is actuated by the usual connections with the feed-wheel 35 as disclosed in said U. S. Patent No. 1,549,248.

We are aware that two-needle straightaway stitching machines have been proposed having two rotary chain-stitch loopers of right- and left-hand formation arranged face-to-face for cooperation each with its respective needle. Such two-needle stitch-forming mechanism has not, however, been heretofore made to function in combination with a button-clamp for vibrating the work in opposite directions across the plane of the needles. It is, of course, simple enough to form a succession of single thread chain-stitches with a rotary chain-stitch looper when the work is fed in the direction of motion of the looper-beak in seizing a needle-loop.

In making a back-stitch, that is, a stitch made when the feed of the work is opposite to the direction of motion of the looper-beak in seizing a needle-loop, difficulties are encountered and a loop-positioner must be resorted to to carry the

limbs of the previous needle-loop held by the looper to the opposite side of the needle, so that the looper-beak may seize a new loop from the needle before passing into the previous loop held spread by the looper. No loop-positioning means has or have, however, been heretofore provided which will function in combination with two needles and two face-to-face rotary chain-stitch loopers in the production of two entirely separate groups of button-fastening stitches.

The foregoing specification is to be read in an illustrative sense and not in limitation of the invention; it being obvious that various modifications within the scope of invention will occur to those skilled in the art.

Having thus set forth the nature of the invention what we claim herein is:—

1. In a two-needle button-sewing machine, in combination, stitch-forming mechanism including a pair of coplanar reciprocating needles and two opposed rotary chain-stitch loopers, a button-clamp, means to relatively vibrate the needles and button-clamp transversely of the plane of the needles, and means to simultaneously position the limbs of both expanded needle-loops relative to their respective needles so that each looper after seizing a needle-loop from its respective needle will pass it through the previously seized and expanded loop on the looper.

2. In a two-needle button-sewing machine, in combination, stitch-forming mechanism including a pair of coplanar reciprocating needles and two opposed rotary chain-stitch loopers, a button-clamp, means to relatively vibrate the needles and button-clamp transversely of the plane of the needles, and means to simultaneously position the upper portions of the limbs of both expanded needle-loops between the descending needle-paths in carrying such limbs across the plane of the needles in the direction in which the looper-beaks move to seize new needle-loops.

3. In a two-needle button-sewing machine, in combination, stitch-forming mechanism including a pair of coplanar reciprocating needles and two opposed rotary chain-stitch loopers each having an axial shank and a loop-spreading shoulder adjacent the base of said shank, a button-clamp, means to relatively vibrate the needles and button-clamp transversely of the plane of the needles, and means to simultaneously position the upper portions of the limbs of both expanded needle-loops between the descending needle-paths in carrying such limbs across the plane of the needles in the direction in which the looper-beaks move to seize new needle-loops.

4. In a two-needle button sewing machine, the combination with a pair of reciprocating needles, of two opposed rotary chain-stitch loopers, a button-clamp and means to vibrate it transversely of the plane of the needles, and means to position the limbs of the two expanded needle-loops between the paths of the descending needles following a movement of the button-clamp in a direction opposite to the direction of loop-seizing motion of the looper-beaks.

5. In a two-needle button-sewing machine, in combination, stitch-forming mechanism including a pair of coplanar reciprocating needles and two opposed rotary chain-stitch loopers, a button-clamp, means to relatively vibrate the needles and button-clamp transversely of the plane of the needles, a Y-shaped loop-positioner having its stem transverse to the plane of the needles, and means to move said loop-positioner lengthwise of its stem across the plane of the

needles to a position in which said stem lies between the paths of the needles.

6. In a two-needle button-sewing machine, in combination, stitch-forming mechanism including a pair of coplanar reciprocating needles and two opposed rotary chain-stitch loopers, a button-clamp, means to relatively vibrate the needles and button-clamp transversely of the plane of the needles, a Y-shaped loop-positioner having its stem transverse to the plane of said needles, and a pair of needle-guards carried by said loop-positioner and disposed at opposite sides of and spaced from said stem.

7. A button-stewning machine having a pair of needles, right- and left-hand rotary chain-stitch loopers arranged face-to-face for cooperation with said needles, a button-clamp, means to vibrate said button-clamp transversely of the plane of the needles, and means to position the spread limbs of both needle-loops at that side of the plane of the needles toward which the newly seized needle-loops are carried by the loopers.
